UNITED STATES PATENT OFFICE.

MARTIN J. FRAND, OF CAMDEN, NEW JERSEY.

DESIGN FOR A ROOF-PEAK.

SPECIFICATION forming part of Design No. 20,695, dated April 28, 1891.

Application filed March 7, 1891. Serial No. 384,162. Term of patent 3½ years.

To all whom it may concern:

Be it known that I, MARTIN J. FRAND, a citizen of the United States, residing at Camden, in the county of Camden and State of New Jersey, have invented and produced a new and original Design for a Roof-Peak, of which the following is a specification, reference being had to the accompanying perspective drawing, forming part thereof.

5 The design is for the peak of a roof. It consists of the sides A, inclined to each other at the same angle as the roof to which it is to be applied. The top or joint is a rope-like ornamentation C of several strands *a*, which are

united by winding or twisting around each other, and the bottom edges terminate in angular pieces or strips B.

I claim—

The design for a roof-peak herein shown and described, the same comprising the inclined 20 sides A, which join in a rope-like ornamentation C, and the angular bottom pieces B.

In testimony whereof I affix my signature in presence of two witnesses.

MARTIN J. FRAND.
